ACHILLE KNAPEN, OF BRUSSELS, BELGIUM, ASSIGNOR TO COMPAGNIE GÉNÉRALE D'
ASSECHEMENT & D'AÉRATION, SOCIÉTÉ ANONYME, OF PARIS, FRANCE.

MEANS FOR DRYING BUILDINGS.

Application filed July 27, 1925, Serial No. 46,269, and in Belgium August 2, 1924.

This invention relates to a method of drying buildings by means of single branched evaporation channels or siphons disposed in the thickness of the walls. In methods of this type, employed up to the present, use has generally been made of inclined channels, closed at their upper end within the wall and the drying effect was obtained by the circulation of air inside the channel, the air entering into the latter being successively charged with moisture and then flowing out, on account of its increased density, along the lower side of the channels, to escape outside the wall, taking with it the moisture with which it has become saturated.

Experience has shown that the results obtained by these methods vary a great deal, the action of the drying siphon being rapid in some cases, in others particularly slow and sometimes even negative, that is to say bringing back moisture into the wall.

The inventor has sought to find the cause of these unsatisfactory and varying results and has observed from numerous experiments that, in the event of insufficient drying, the channel or siphon formed in the thickness of the wall generally only exerted its action over a part of its length the upper part of the channel forming a cushion of inert air, that is to say which takes no part in the circulation. It is possible to prove, by experiment, that these disadvantages are due in most cases to a bad slope of the evaporation channels. In fact if account is taken of the fact that the layers of atmospheric air which have access to the drying channel are horizontal layers, it is easy to understand that if a layer of air under consideration, entering in the form of a sheet into the channel, under the upper edge of the outer orifice of the latter, cannot reach the inner end of the channel it can only give rise in the latter to a reduced circulation, the whole volume of air confined in the upper end of the channel being unable to take part in the circulation.

According to the invention, the drying channels or siphons formed in the thickness of the walls, in order to overcome this disadvantage, are given an inclination such that a horizontal sheet of air entering into the chan-

nel tangentially to the upper bounding line of the outlet orifice may escape with a predetermined thickness equal to that which it possesses when it enters through the opposite end of the channel if the latter is not closed. 55

Under these conditions the sheet of air considered may exert its drying action over the whole length of the channel and become charged gradually with moisture the objectionable influence of the inner cushion of air 60 being effectively overcome. The observing of this condition gives the further result that practically the inclination of the drying channel or siphon must be in an inverse ratio to the length of the latter in the thickness of 65 the wall, the thermal differences between the air inside the wall and the air in contact with its sides being as much greater as the wall is thicker and the materials denser.

In the practical embodiment of the invention, this inclination varies, in addition, according to the position occupied by the drying channel in the wall, that is to say in such a way as to take into account the thermal and hygrometric variations of the layers of air 75 circulating in the channel. In practice, this inclination varies according as the drying channel is placed at the lower part or at the upper part of a wall or again inside or outside a room in such a way that the moving 80 sheet of air, tangential to the end orifices of the drying channel or siphon possesses thicknesses varying to a certain extent according to the conditions to be obtained and the level or the height at which it must work. 85

The effect of the drying channel or siphon is considerably increased when these parts are given a particular cross sectional outline giving rise to one or more hygroscopic centres formed by masses suitably disposed for accumulating moisture and in such a way as to assist the evaporating action under the conditions stated above. 90

The accompanying drawings illustrate by 95 way of example forms of construction of the invention.

Figure 1 shows diagrammatically, in perspective, a channel having two different inclinations in order to establish by comparison 100 the conditions the inclination of the channel

must fulfil in order to obtain the result sought by the invention.

Figure 2 shows the drying channels arranged in a wall, these channels being placed under the desired conditions to obtain the working of the method.

Figures 3 and 4 are cross sections of embodiments in which the evaporation channels are formed so as to have masses forming hygroscopic centres which assist, by attracting the surrounding moisture in the zone of their radius of action, the saturation of the sheet of air circulating in the evaporation channel.

With reference to Figure 1 and assuming that a is a channel open at both ends and arranged at a predetermined slope, it is easily to see that a horizontal sheet of air b of suitable thickness entering this channel tangentially to the upper bounding line c of the air inlet aperture d will meet the lower bounding line e of the channel at a point f situated at a considerable distance from the outlet aperture g . It is obvious that under these conditions the layer of air f , assuming that it can become saturated with moisture during its travel through the channel a cannot exert any action upon the layers of air contained in the upper part h of the channel, since this air, cooled by the evaporation from the surface of contact will flow directly along the lower generating line as its density increases.

The same would not hold if the channel a was inclined as shown at a^1 in such a manner that the layer of air b , tangential to the upper part of the inlet orifice d , was also tangential to the inner end i of the outlet aperture g . Under these conditions the action of the sheet of air will be felt over the whole length of the channel and as a consequence its drying action will be stronger than in the case of a steeper inclination similar to the one shown for the channel a in Figure 1.

Figure 2 shows the embodiment of this principle in the case of a wall j . As shown in this figure, according to the invention the drying channels or siphons k are given an inclination such that the condition mentioned with reference to the channel a^1 in Figure 1 is satisfied: moreover, as shown in Figure 2, in order to take into account the thermal and hygrometric differences which may exist at different points in the height of the wall k , the inclination of the drying channels may vary according to their position upon the height of the wall j in such a manner that for a channel k , placed at the upper part of the wall, the thickness of the layer of air b is less, for example, than the corresponding thickness of air in a channel placed at the lower part of the wall. It is the thickness of this layer of air which, according to the thermal and hygrometric conditions and the level of the part in question will determine the rapidity and efficiency of operation of the drying channel or siphon.

Figure 2 shows in dotted lines at k^1 the alteration in inclination of such a channel, in the case of a wall of greater thickness, in order to satisfy the condition stated.

Naturally the method of constructing the evaporating channels mentioned above requires that these channels be formed in a homogeneous element of constant porosity, preferably formed separately and then placed in the building to be dried in which channels or cavities such as the hole k shown in Figure 3 are previously prepared. In this case the element which forms the evaporating channel may consist for example of a brick specially constructed and subsequently placed in the thickness of the wall.

Figure 3 shows a brick of this type of triangular form. This brick s which is provided with a circular channel t is placed in a circular cavity k formed in the wall. It may be built into this cavity by means of cement or mortar of porosity predetermined according to the case.

When use is made of evaporation channels thus constructed, it is advantageous to make the member comprising the evaporating channel of special form, for example of polygonal form of the type shown in Figure 4 for the formation of a channel k .

Figure 4 shows a construction of this type in which the member or brick s forms hygroscopic centres t^1 which are distributed at the most suitable points to assist condensation and the accumulation of moisture in the brick. The distributions of these centres t^1 as shown in Figure 4 has the advantage over the distribution obtained by adopting the triangular form shown in Figure 3 that the mass forming the hygroscopic centre of greatest accumulation of moisture is at the upper part of the member forming the evaporating channel while two other masses form centres of smaller hygroscopic attraction arranged symmetrically are carried a little below the level of the horizontal diameter of the channel. In the example shown in Fig. 4, the upper surface of the channel t is provided with angular teeth u ; these angular grooves are provided for the purpose of increasing the evaporating and consequently cooling surface and of consequently accelerating the removal of moisture which accumulates in the saturated brick, due to the attraction it exerts, on account of its special shape, upon the moisture contained in the surrounding parts of the wall is constantly drawn into the radius of action of the member forming the siphon.

What I claim is:

1. In a building wall, means for drying said wall comprising a conduit therein extending transversely from one surface of the said wall to a point within the other surface of the said wall, said conduit being inclined with its inner closed end relatively higher than its outer

open end and of such inclination that the lowermost point of its inner end is substantially below the uppermost point of its outer end whereby a horizontal sheet of air entering the conduit may reach the innermost end of the conduit and establish a circulation throughout the entire length of the conduit.

2. In a building wall, means for drying said wall comprising a conduit therein extending transversely from one surface of the said wall to a point within the other surface of the said wall, said conduit being inclined with its inner closed end relatively higher than its outer open end and of such inclination that the lowermost point of its inner end is substantially below the uppermost point of its outer end, the inclination being inversely proportional with respect to the length of the conduit whereby a horizontal sheet of air entering the conduit may reach the innermost end of the conduit and establish a circulation throughout the entire length of the conduit.

3. In a building wall, means for drying said wall comprising a plurality of conduits arranged at varying heights therein and extending transversely from one surface of said wall to a point within the other surface of said wall, said conduits being inclined with their inner closed ends relatively higher than their outer open ends respectively and of such inclinations that the lowermost point of their inner ends are substantially below the uppermost point of their outer ends whereby a horizontal sheet of air entering the conduits may reach the innermost ends thereof and establish a circulation throughout the entire length of the conduit, the inclination of said conduits increasing proportionately to their heights in said wall whereby a thicker sheet of air may enter the lower conduits relatively to the higher conduits.

In testimony whereof I have affixed my
45 signature.
